UNITED STATES PATENT OFFICE.

GEORGE W. RAMSEY, OF PEORIA, ILLINOIS.

TYPE-WRITER RIBBON.

1,130,020.

Specification of Letters Patent.

Patented Mar. 2, 1915.

Application filed August 27, 1909. Serial No. 514,962.

To all whom it may concern:

Be it known that I, GEORGE W. RAMSEY, residing at Peoria, in the county of Peoria, State of Illinois, (whose post-office address is 902 Westory Building, Washington, District of Columbia), have invented certain new and useful Improvements in Type-Writer Ribbons, of which the following is a specification.

10 This invention relates broadly to the art of printing and specifically to the type writer, and kindred arts.

The object of the invention is to provide a means for forming a distinctive imprint, which distinction is not dependent on the type face or upon the color of the transferred pigment.

A further object is to provide a means for causing the carbon, or duplicate copy, to 20 be an indicatively true copy of the original sheet.

This invention, which is believed to be broadly new, is for this reason susceptible of structural changes, without departing from 25 the scope thereof, but a preferred form will be hereinafter specifically described by reference to the drawings which form a part of this specification, and the scope of the invention will be indicated by the claims.

30 In the accompanying drawings in which like numerals represent like parts throughout the several figures:—Figure 1, is a diagrammatic cross section of the printing mechanism of a typewriting machine. Fig. 35 2, is an open work modification of an inking ribbon. Fig. 3, is a representation of a section of multi-color printing ribbon, showing the improved structure. Fig. 4, is a cross section through a portion of the ribbon, showing one manner of weaving same. Fig. 5, indicates the form of imprint caused by said ribbon.

40 In the device herein set forth, the character of a particular color of ribbon field is indicated by means of a particular kind of distinctive weave for said color. The distinctive feature of the ribbon is woven of such material as will not be crushed by the blow of the type, and the weave is adapted 45 to imprint its form upon the paper when the ribbon is struck by a type character. In this manner the structure of the ribbon becomes a printing face whose distinguishing characteristic is independent of said color of the impregnating pigment. By introducing 50 fine steel piano wires *a* at definite spaced

intervals between the warp threads of the ribbon, a ribbon is formed that will produce a distinguishing imprint, and will cause the distinguishing characteristic to be also imprinted through on a carbon or duplicate sheet. And by varying the directions of the piano wires with relation to the ribbon, in each different field of color of the ribbon, the carbon becomes an indicatively true copy 65 of the original sheet.

Fig. 1, is a diagrammatic representation of the printing elements of a typewriting machine, in which the key lever 1, is fulcrumed on a key lever rod 2, and is adapted 70 to operate the sub-lever 3, which in turn operates the type bar 5, through the links 4. As the actuation of these parts are so well known to those skilled in the art, a further description is thought to be unnecessary. 75 The platen 6, is shown as carrying thereon an original sheet 9, a carbon sheet 8, and a duplicate sheet 7.

Beneath the key lever 1, is a universal bar 10, which connected by links 11, with the 80 rocker lever 12, vibrates the ribbon carrier, or vibrator 13. Thus at each stroke of the key the ribbon is carried to the printing point. The ribbon change device 14, I have indicated as being carried by the ribbon vibrator itself in such manner that the ribbon A may be shifted to any desired printing field after the manner well known in the typewriting art. As this mechanism forms no part of my invention I have illustrated 85 the above parts in a diagrammatical manner. The ribbon which is shown in cross section in the vibrator, is disclosed as having two printing fields of different structure. The upper field A representing the ordinary 90 plain or black field of the printing ribbon. The lower portion B is of a differently colored field and is shown as containing piano wires in a manner, and for a purpose, as will be more fully explained later in this specification. 95

In Fig. 3, a printing ribbon is illustrated in which three different printing fields are diagrammatically represented. In this figure a pattern of the weave which will be imprinted by the impact or imprint of the type character, is a design of longitudinal uniformity, that is, the entire longitudinal length of the particular printing field is of the same design. This invention however, 105 also contemplates a design that may vary in the same longitudinal field, and thus the im- 110

print will be changed automatically as the ribbon is being fed through the ribbon guide, as it is being wound on the ribbon spools, in the usual manner.

5 Referring more particularly to Fig. 3, field A represents the black portion of the ribbon; field B indicates the red portion of the same ribbon; C indicates the purple or other colored field of the ribbon. The black 10 portion A of the ribbon is woven in the usual manner. In the red portion B of the ribbon, piano wires (a) of small cross section are introduced among the warp threads at determinate intervals, for example at 15 every third thread. In the purple field C, of the ribbon the piano wires (a) have a direction different from that in the red printing field. It is also obvious that the 20 printing ribbon formed to determine the character imprint by the structure of the ribbon, may be made in a single color and yet obtain all of the advantages of a multi-color ribbon, without any of the disadvantages of the same. But again referring to 25 the combination of the multi-color with the structural distinction, each multi-color field may be formed of a different structure.

Referring to Fig. 4, the warp threads (a) indicate piano wires; the threads (b) 30 are formed of cotton, silk or other fibrous threads. The filler thread (c) is bound between the warp threads (a) and (b) by means of the woof threads (d) and (e). The face of the ribbon beneath which im- 35 mediately lies the piano wires (a), is adapted to be used as the printing face. The face of the ribbon opposite thereto becomes, because of the filler threads c and the warp threads b, a pad adapted to hold ink and a 40 cushion against which the type strikes, thereby preventing said type face from being destroyed by direct contact with the piano wires. It will be seen that I may vary the direction of the wires in the ribbon, and thereby form a distinctive variation 45 in the character of imprint for each color of the printing ribbon.

Fig. 2, indicates a modification of the method of varying the character of imprint from the printing ribbon. In this 50 modification one field of the ribbon (d), corresponding to the field b in Fig. 3, is woven in such manner that the threads are more or less separated from each other, 55 and are adapted thereby to produce a varied or uneven imprint. The other field, corresponding to a Fig. 3, is woven in the usual manner as is well known in the art of type-writing ribbons.

60 I have found that it is not necessary to form the character distinguishing threads or wires (a) of piano wires, since tightly twisted threads of any fibrous substance, being sufficiently solid to transfer its char- 65 acter of imprint on the paper and through

to the duplicate sheet, will accomplish the desired result.

In Fig. 5, (f) indicates the usual character of imprint from the black field of the ribbon. (g) indicates the character of imprint from the red field of the ribbon, the said imprint from this field showing an uneven appearance because of the longitudinal wires in the red field of the ribbon. (h) indicates the character of imprint from 75 the purple field of the printing ribbon, which shows a different appearance from that shown in the other fields.

A printing ribbon constructed in the manner as above set forth will cause a carbon 80 or duplicate sheet to indicate which field of the ribbon was struck by the type at the printing point, and thus the carbon sheet becomes an indicatively true copy of the original sheet. This invention also 85 contemplates the use of a single colored ribbon having various printing fields therein woven in such manner as to cause each field to make a different imprint. In this manner the full advantage of multi-color work 90 could be attained and yet have the work in a single color. This is of advantage and use in certain official papers where multi-colored inks are not allowed.

As many changes could be made in the 95 above structure and many apparently widely different embodiments of this invention could be made without departing from the scope thereof, the definite matter contained in the above description and 100 shown in the accompanying drawings is to be taken as illustrative and not in a limiting sense.

I claim as my invention:—

1. A printing ribbon carrying pigments, 105 said ribbon having distinct printing fields, each field containing structural means to determine the character of imprint from said field.

2. A type writer ribbon having different 110 printing fields composed of materials of different degrees of hardness, said materials constituting means for differentiating imprints from the different printing fields.

3. A typewriter ribbon comprising a 115 woven fabric, coloring matter of different colors impregnated in different areas of said fabric, and means in said different color areas for showing in an imprint an index of the color field struck when the imprint is made.

4. A type writer ribbon carrying a pigment and being formed with a plurality of printing fields, said fields containing structural characteristics adapted to produce a 125 distinctive imprint for each of said fields.

5. In a multi-color type ribbon, means in each printing field adapted to differentiate on a carbon sheet the corresponding imprints of different colors on the original sheet. 130

6. In a type writer ribbon, means to produce a non-uniform imprint of a uniform color when said ribbon is struck by an integral type character.
- 5 7. A type writing machine including, a platen, a type, means to operate said type, and means to cause an imprint on a duplicate sheet to indicate a characteristic of the imprint made on an original sheet.
- 10 8. In a type writing machine the combination of, a type bar, a type, type bar operating means, a platen, an ink ribbon having multiple printing fields, and means to indicate on a duplicate sheet which of said fields 15 of the ribbon was struck by the type at the printing point.
- 20 9. In a type writing machine the combination of a type bar, a type, operating means for said type bar, a platen, a multi-color ribbon, and means to indicate on a duplicate sheet a characteristic of the imprint on the original sheet.
- 25 10. In a type writing machine the combination of a type bar, a type, operating means for said type bar, a platen and a ribbon, said ribbon being constructed to cause an imprint of different densities of a single color to be made from a single type face during a single printing operation.
- 30 11. In the type writer art, the combination of a platen, a type, type operating means, duplicating means, a multifield ribbon and means to produce indications on a duplicate sheet when a change is made from 35 one field to another of said ribbon at the printing point.
- 40 12. In a type writing machine the combination of, a type bar, operating means for said type bar, a type, a platen, and means to cause an impression from said type to present an imprint of varied density.
- 45 13. In a type writer, in combination, a type bar, a type, operating means for said type bar, a platen, and means operating between said type and said platen adapted to change the character of the type imprint of a single color.
- 50 14. A type writing machine including the combination of a platen, an integral type character, and means to produce printing impressions of different aspects in a given color from different parts of the said character.
- 55 15. In a printing device the combination of a platen, a type character, an ink carrying means, said ink carrying means having a plurality of printing fields, coloring matter carried by said ink carrying means, each of said fields having means to cause a dis-
- tinct character of imprint, said distinction 60 being due to the difference in structure in the several printing fields of the said ink carrying means.
- 65 16. A type writing machine including the combination of a platen, an integral type, an inking means, colored ink carried by said ink carrying means and means to produce simultaneously different printing effects from different parts of the face of the said integral type character. 70
- 75 17. In the type writing art, the combination of a platen, a type, duplicating means, and means to produce an indication on a duplicate sheet when a change in the color of imprint is made on the original sheet. 75
- 80 18. A type writing machine, including the combination of a platen, an integral type, operating means for said type, a ribbon carrier, means for vibrating said ribbon carrier, a multi-field ribbon, and means to produce a different printing effect from different parts of the face of said integral type character while printing through a single field of said ribbon.
- 85 19. In a type writing machine, the combination of, a type bar, a type, type bar operating means, a platen, a multi-color ink ribbon, means for vibrating said ribbon to and from the printing point, and means to cause the imprint through a transfer medium on a 90 duplicate sheet to indicate a characteristic of the imprint on the original sheet.
- 95 20. In the type writing art, the combination of a platen, a type, type operating means, duplicating means, a multi-color ribbon, means for vibrating said ribbon, and means to produce indications on a duplicate sheet when a change is made from one field to another of said ribbon at the printing point. 100
- 105 21. In a typewriting machine the combination of a type having an integral type face, a platen, and means having a characteristic printing surface adapted to be interposed between the type face and the platen to cause the face of the character imprinted to be different from the face of the type making the imprint.
- 110 22. As a new article of manufacture a typewriter ribbon formed with a plurality of fields each having a printing face adapted to imprint a distinctive predetermined configuration.

GEORGE W. RAMSEY.
